(57) CLAIM

The ornamental design for footwear, as shown and described.

DESCRIPTION

FIG. 1 is a front perspective view of footwear showing my new design;

FIG. 2 is a left side view of the footwear shown in FIG. 1;

FIG. 3 is a right side view of the footwear shown in FIG. 1;

FIG. 4 is a front view of the footwear shown in FIG. 1;

FIG. 5 is a rear view of the footwear shown in FIG. 1; and,

FIG. 6 is a top view of the footwear shown in FIG. 1.

The broken line showing of the heel, heel cap, sole, buckle, buckle holes, and portion of the straps is for illustrative purposes only and forms no part of the claimed design.

1 Claim, 6 Drawing Sheets
